UNITED STATES PATENT OFFICE.

CHARLES FREDERICK GEDNEY, OF BROOKLYN, NEW YORK, ASSIGNOR TO
MATTHEW J. WHITTALL, OF WORCESTER, MASSACHUSETTS.

DESIGN FOR CARPET.

SPECIFICATION forming part of Design No. 24,561, dated August 13, 1895.

Application filed June 28, 1895. Serial No. 554,148. Term of patent 3½ years.

To all whom it may concern:

Be it known that I, CHARLES FREDERICK GEDNEY, residing at Brooklyn, county of Kings, State of New York, have invented and produced a new and original Design for a Pattern to be Wrought into Wilton and other Carpetings, in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of the body A and the border B.

The body A is decorated with circular and diamond shaped ornamental figures alter-

nating, surrounded with small geometric figures.

The border B shows similar geometric figures.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A, and the border B, substantially as shown.

CHARLES FREDERICK GEDNEY.
